ATOMIZING DEVICE

William H. Rose, Jersey City, N. J.

Application February 25, 1942, Serial No. 432,212

8 Claims. (Cl. 299—88)

My invention relates to atomizers and refers particularly to devices of the general character described, in which a liquid is retained in, and carried by, an absorbent material.

Atomizers of this character possess many advantages over those in which a mass, or body, of free liquid is present, over or through which air is forced, among which are the freedom from spilling of the liquid, the better atomization obtained because of the passage of air over a large surface of liquid, a reduction in loss of liquid by evaporation, and the production of increased and improved atomization by presenting a more complete and constant mixture of air and liquid at the point of atomization.

One disadvantage experienced in atomizers of this general character is the tendency of the absorbent material to pack over the exit opening, thus preventing the free passage of the air and liquid mixture through the exit opening, resulting in uneven and unsatisfactory atomization.

Another disadvantage experienced in these atomizers is that when the mixture of air and liquid is forced directly through an exit opening of the casing connected directly with the main passageway in which the air and liquid are commingled, the spread of the atomized mixture is insufficient and the mixture has a tendency to be emitted in the form of a stream.

Another disadvantage in devices of this character is that as the passage of air through the device, when operated, is quite rapid, the last portion of the air has not had sufficient time to extract the proper amount of liquid from the absorbent material, and hence there is a deficiency of liquid at the exit point, producing an uneven spread and composition to the atomized mixture.

My invention relates to atomizers in which the above-mentioned and other disadvantages of devices of this character have been overcome, and which produce even and constant mixtures, which, when atomized, produce superior atomization with constant and greater spread, all of which will be evident upon a consideration of my specification and drawing, in which modified forms of my devices are clearly shown and in which similar parts are designated by similar numerals.

Figure 1 is a vertical section taken through one form of a device of my invention.

Figure 2 is a section taken through the line 2—2 of Figure 1.

Figure 3 is a top plan view of one form of a cover disk for use in my devices.

Figure 4 is a perspective view of one form of a

mass of absorbent material adapted for use in my devices.

Figure 5 is a top plan view of an exit disk of my devices.

Figure 6 is a fragmentary vertical section taken through a modified form of my devices.

Figure 7 is a vertical section taken through a modified form of a device of my invention.

Figure 8 is a section through the line 8—8 of Figure 7.

The particular form of a device of my invention shown in Figures 1, 2, 3 and 5 comprises a cylindrical casing having the side 10, one end of the casing having an end member 11 with a centrally positioned opening 12, the other end of the casing being open.

Positioned within the casing and abutting upon the inner face of the end member 11 is a disk or spacer 13 having an opening 14 therein of smaller diameter than the diameter of the opening 12 of the end member 11. This disk 13 may be of any suitable material such as fiber, glass cloth, or fine wire mesh and I have found paper particularly adapted for this purpose.

Positioned within the casing and abutting upon the disk 13 is an elongated octagonal member 15 extending toward the open end of the casing. This octagonal member is composed of any suitable liquid absorbing material and I have found felt to be particularly suitable for this purpose. A longitudinal opening 16 extends through the absorbent member 15 in alignment with the opening 14 of the disk 13, the opener 16 being of greater diameter than that of the opening 14.

It will be noted that there is thus formed four longitudinal channels, or spaces, 17, 17, between the casing side 10 and the faces of the absorbent member 15.

Positioned upon the outer exposed face of the absorbent member 15, is a cover disk 18 which may or may not be of absorbent material, but if it is of non-absorbent material it should have the radiating gutters, or recesses, 19, 19.

This disk 18 has a centrally positioned opening 20 in alignment with the opening 16 of the absorbent member 15.

The outer end of the casing carries a compressible rubber ball 21, the thickened end 22 of which is positioned within the outer end of the casing. This thickened end portion 22 has a longitudinal opening 23 in alignment with, and of a greater diameter than, the opening 20 of the disk cover 18.

One way of charging this device with a liquid is to depress the ball 21, insert the forward end

of the device into the liquid and release the pressure upon the ball, thus driving a quantity of liquid through the openings 12 and 14 into the opening 16 from which it is absorbed by the absorbent member 15.

In operation, the ball 21 is pressed thus forcing some of its air content through the opening 23, the radiated passageways 19, 19 through the spaces 17, 17, 17, 17, between the disk 13 and the end member 11, and outwardly through the opening 12 in the form of a spray. The remainder of the air passing through the opening 23, the opening 20, the opening 16 and the openings 14 and 12 in the form of a spray. Some of the air may also pass between the disk 13 and the absorber material 15. All of this air in passing through the device passes over the absorbent material and carries a proportion of liquid with it to produce a fine spray effect at the exit opening.

The modified form of a device of my invention shown in Figures 2, 4, 7 and 8 is similar to the previously described form of my device, as indicated by corresponding numerals, but differs from it in the following manner. This modified form of my device has a plurality of disks, or spacers, 13, 13, 13, having aligned holes 14, 14, 14 through them. These disks may be made from various materials which may, or may not be absorbent. The absorbent member of this device consists of a plurality of round disks 24, 24 of absorbent material having aligned openings therethrough. This form of my device does not have a free end disk cover, the portion 22 of the rubber ball 21 abutting upon the free face of the last absorbing disk 24.

In the operation of this form of my device the air passes from the ball 21 through the opening 23, the openings 16, 16, the openings 14, 14, and the opening 12 in the form of a fine spray.

Figure 6 illustrates a modified form of a device of my invention, adapted for the charging of the absorbent material with a liquid without the necessity of inserting the exit end of the device into the liquid.

In this form of my device an opening is made in the side member 10 of the casing, which is fitted with the extended threaded neck 25, which is adapted to thread with the neck 26 of the liquid container 27.

When it is desired to charge the absorbent material, the device and liquid container are placed in combination as shown in Figure 6, and the device is reversed allowing some of the liquid to pass with the device and into the absorbent material 15, or the device is shaken to allow some of the liquid to be splashed into the absorbent material. When sufficient liquid has been inserted into the device, the liquid container is removed and a suitable closure is threaded upon the device neck 25.

If desired liquid may also be introduced by removing the collapsible rubber ball device and pouring liquid through the thus produced open end of the casing.

While I have shown my device with a collapsible rubber ball as a means for producing the atomizing effect, it is evident that other suitable means may be employed for this purpose.

It is to be noted that a valuable feature of my devices is that the absorbent material can not clog up, or partially close, the exit openings in the disks at the exit end, thus being accomplished by having the opening in that portion of the absorbent material abutting upon a disk of greater diameter than the disk opening.

It will also be noted that as the end exit opening of my devices is of greater diameter than the opening in the disks, or spacer, the mixture of air and liquid in its atomized condition will form a greater spread than would be the case if the exit opening led directly into the passageway 16 of the liquid-absorbent material.

I do not limit myself to the particular size, shape, number, arrangement or material of parts 10 as shown and described as these are given solely for the purpose of clearly describing the devices of my invention.

What I claim is:

1. In an atomizer, in combination, a casing having an end member with an exit opening therethrough; a mass of liquid-absorbent material within said casing having an opening therethrough in alignment with said exit opening; spacing means immediately between said end member and said liquid-absorbent mass having an opening therethrough in alignment with said exit opening and said liquid-absorbent mass opening, the diameter of said spacer opening being less than the diameter of said end opening and of said liquid-absorbent mass opening and the diameter of said liquid-absorbent mass opening being greater than the diameter of said end opening; and pressure producing means on said casing at the end opposite said exit opening.

2. In an atomizer, in combination, a casing having an end member with an exit opening therethrough; a mass of liquid-absorbent material within said casing having an opening therethrough in alignment with said exit opening; and liquid-absorbent spacing means between said end member and said liquid-absorbent mass having an opening therethrough in alignment with said exit opening and said liquid-absorbent mass opening, the diameter of said spacer opening being less than the diameter of said end opening and of said liquid-absorbent mass opening.

3. In an atomizer, in combination, a casing having an end member with an exit opening therethrough in alignment with said exit opening; a plurality of spacing means immediately between said end member and said liquid-absorbent mass having an opening therethrough in alignment with said exit opening and said liquid-absorbent mass opening, the diameter of said spacer opening being less than the diameter of said end opening and of said liquid-absorbent mass opening and the diameter of said liquid-absorbent mass opening being greater than the diameter of said end opening; and pressure producing means on said casing at the end opposite said exit opening.

4. In an atomizer, in combination, a casing having an end member with an exit opening therethrough; a mass of liquid-absorbent material within said casing having an opening therethrough in alignment with said exit opening; and a plurality of liquid-absorbent spacing means between said end member and said liquid-absorbent mass having an opening therethrough in alignment with said exit opening and said liquid-absorbent mass opening, the diameter of said spacer opening being less than the diameter of said end opening and of said liquid-absorbent mass opening.

5. In an atomizer, in combination, a casing having an end member with an exit opening therethrough; a mass of liquid-absorbent material within said casing forming a plurality of

longitudinal passageways with said casing and having an opening therethrough in alignment with said exit opening; spacing means immediately between said end member and said liquid-absorbent mass having an opening therethrough in alignment with said exit opening and said liquid-absorbent mass opening, the diameter of said spacer opening being less than the diameter of said end opening and of said liquid-absorbent mass opening and the diameter of said liquid-absorbent mass opening being greater than the diameter of said end opening; and pressure producing means on said casing at the end opposite said exit opening.

6. In an atomizer, in combination, a casing having an end member with an exit opening therethrough; a plurality of stacked liquid-absorbent material within said casing having an opening therethrough in alignment with said exit opening; spacing means immediately between said end member and said liquid-absorbent mass having an opening therethrough in alignment with said exit opening and said liquid-absorbent mass opening, the diameter of said spacer opening being less than the diameter of said end opening and of said liquid-absorbent mass opening and the diameter of said liquid-absorbent mass opening being greater than the diameter of said end opening; and pressure producing means on said casing at the end opposite said exit opening.

7. In an atomizer, in combination, a casing

having an end member with an exit opening therethrough; a plurality of stacked liquid-absorbent material within said casing having an opening therethrough in alignment with said exit opening; and liquid-absorbent spacing means between said end member and said liquid-absorbent mass having an opening therethrough in alignment with said exit opening and said liquid-absorbent mass opening, the diameter of said spacer opening being less than the diameter of said end opening and of said liquid-absorbent mass opening.

8. In an atomizer, in combination, a casing having an end member with an exit opening therethrough; a plurality of stacked liquid-absorbent material within said casing forming a plurality of longitudinal passageways with said casing and having an opening therethrough in alignment with said exit opening; spacing means immediately between said end member and said liquid-absorbent mass having an opening therethrough in alignment with said exit opening and said liquid-absorbent mass opening, the diameter of said spacer opening being less than the diameter of said end opening and of said liquid-absorbent mass opening and the diameter of said liquid-absorbent mass opening being greater than the diameter of said end opening; and pressure producing means on said casing at the end opposite said exit opening.
